MILK BOTTLE

Joseph M. Sansby, St. Paul, Minn.

Application July 1, 1935, Serial No. 29,272

2 Claims. (Cl. 215—31)

This invention relates to containers of the type in which liquid foods are stored and periodically dispensed therefrom, the device being particularly adapted for use as a container or bottle for 5 milk, cream and other beverages. Heretofore considerable attention has been paid to the delivery of such bottles to the user in sanitary condition, but the construction heretofore employed has led to contamination of the contents due to 10 the dripping or flow during the pouring of the contents onto the outside of the bottle and upon the surfaces which must be gripped to dispense the contents.

It is an object of this invention to provide a 15 novel container or bottle of this class adapted to guard against contamination of the contents by preventing the flow thereof to the exterior surfaces which are normally grasped and by guarding against the grasping of such portions of the 20 container as are reached by the contents.

A particular object is to provide a bottle having 25 a neck so constructed that the drip or flow over or onto the outside is prevented and having a flange whereby application of the hand 30 of the user to the lip or spout portion of the bottle is guarded against.

Referring to the accompanying drawing which 35 illustrates the best form of my device at present known to me:

Figure 1 is a side elevation showing the neck or upper portion of my improved container, and

Figure 2 is a central, vertical section through 35 the same showing in dotted lines the normal position of a cap or cover, of ordinary form, on the bottle.

My improved bottle has a body portion 3 of 40 ordinary or suitable shape which tapers upward to form a neck 4 adapted to be gripped in pouring from the top opening of the bottle. Above the upper extremity of the neck 4 is an 45 annular guard flange 5 and spaced a substantial distance above the flange 5 is an annular flange 6. Between the flanges 5 and 6 is a substantially 50 reduced portion or groove 7 which is wide enough to prevent the bridging across from one flange to the other of beverages flowing from the neck of the bottle. Sharply angular corners 8 at the top and bottom of the flange 6 are adapted to 55 perform the important function of a drip or flow breaker to eliminate the following of liquid around the flange and down the exterior of the bottle during the pouring operation.

The groove 7 is also sufficiently open and wide to facilitate the cleaning and sterilizing of the bottle in the ordinary washing machines and the upper surface 9 of the lower flange 5 slopes out and down abruptly so as to readily 60 drain off any wash water or other liquid that

may be applied to or reach the groove 7. The drainage of the groove is further facilitated by forming a plurality of radially directed, abruptly sloping grooves 10 in the surface 9. The lower surface of the flange 5 is substantially horizontal and approximately perpendicular to the outer surface of the flange 5 to make the flange more effective in guarding against the application of the hand of the user to the portions of the neck above the flange 5.

The bottle may be closed by the usual or suitable disk cap 11 fitting within an annular, internal recess in the neck of the bottle. The exterior surfaces near the top of the bottle may be protected in transit by an outer cover 12 held in place by a wire or binding member 13 encircling the outer surface of the cover beneath the flange 5. The flange 6 is preferably somewhat greater in diameter than the flange 5 to facilitate the fitting of the cover 12 and also to cause any drip from the flange 6 to fall free of the flange 5 when the bottle is stood upright.

In use, after removal of the disk 11 and cover 12 the contents are dispensed by gripping the neck 4 beneath the flange 5 and pouring from 25 the open neck over the top of the flange 6. By my arrangement of the abruptly angular or sharp edges 8 of the flange 6 the stream of liquid during pouring breaks sharply over the top and does not flow down over the outer surfaces, while 30 the flange 5 guards the upper extremities of the bottle from contaminating by the hand of the user.

Having described my invention, what I claim as new and desire to protect by Letters Patent is:

1. The combination in a liquid dispensing bottle having a neck portion adapted to be grasped, of a guard flange projecting from the normally upper extremity of said neck portion, the top of said flange having drainage grooves sloping 40 steeply out and down radially of the bottle and an annular pouring flange spaced upwardly from said guard and formed with a sharply angular rim adapted to break the flow of liquid during the pouring operation and to guard against the 45 passage of the same upon the surfaces between said flanges.

2. The combination in a bottle for liquid dairy products and the like, said bottle having a neck portion adapted to be grasped, of a guard flange 50 projecting from the normally upper extremity of the said portion, the top of said flange having drainage grooves sloping steeply out and down radially of the bottle and an annular pouring flange spaced upwardly from said guard flange and formed to deflect the liquid from 55 said guard flange during the pouring operation.
